ELECTRIC MOTOR

Original Filed August 17, 1922 2 Sheets-Sheet 2

UNITED STATES PATENT OFFICE.

HENRY K. SANDELL, OF CHICAGO, ILLINOIS, ASSIGNOR TO MILLS NOVELTY COMPANY,
OF CHICAGO, ILLINOIS, A CORPORATION OF ILLINOIS.

ELECTRIC MOTOR.

Original application filed August 17, 1922, Serial No. 582,458. Divided and this application filed June 20, 1924. Serial No. 721,212.

To all whom it may concern:

Be it known that I, HENRY K. SANDELL, a citizen of the United States, residing at Chicago, in the county of Cook and State of Illinois, have invented a new and useful Improvement in Electric Motors, of which the following is a specification.

This invention relates particularly to motors. The improved motor herein shown and described, while it may be employed for other purposes, is well adapted for use in musical machines employing stringed instruments of the violin class, where the motor may serve to operate the bow-shafts at varying speeds.

The present application illustrates one use of the improved motor in connection with a musical instrument of the character mentioned, and constitutes a division of my application No. 582,458, filed in the United States Patent Office, August 17, 1922. The invention will be understood with reference to the accompanying drawings, in which:

Fig. 1 is a vertical sectional view through the improved bow-motor; Fig. 2 is a horizontal sectional view through the bow-motor on the line 2—2 of Fig. 1; Fig. 3 is a vertical sectional view on the line 3—3 of Fig. 1; and Fig. 4 is a diagrammatical view illustrating the circuits which may be employed in connection with the invention.

Referring to the drawings, Fig. 4 shows diagrammatically certain elements of an electrically operated stringed instrument of the violin class, one of the fingering levers, designated 14, and one of the bow-depressing levers, designated 22, being shown. The string of the violin or other instrument is designated 12.

Above each string 12 is a bow member or sounder 15, preferably formed of nested conical celluloid shells, these sounders being secured to the ends of the bow shafts 16, which extend in a direction substantially longitudinally of the strings 12. These bow shafts 16 pass through a journal or bearing formed in the sleeves 18 which partially surround the worm 19, the sleeves 18 being rotatable for a limited distance upon the worm gear 19. At their ends the bow shafts 16 are provided with gears 20 which mesh with and are driven by the worm 19. The worm 19 is journaled in bearings suitably provided in a housing 21 supported on the

bow motor casing, as hereinafter more fully described. From the above description, it will be seen that the bow shafts 16 may be depressed to bring the sounders 15 into engagement with the corresponding strings. Suitable means are provided for this purpose. For example, the levers 22 may be employed, these levers being actuated by electro-magnets 25 when the latter are energized to depress the corresponding bow-shafts 16.

The improved bow motor will be more fully described. The worm 19 which rotates the bow shafts 16 is connected directly through shaft 26 with the rotor 27 of the A. C. induction motor 28, which is housed in a casing 29 supported on the standard 30. The rotor 27 is of the induction motor type, provided with a squirrel cage 29a. The stator 30, which is formed of laminated sheets of a suitable iron, is provided with the teeth 32 which form the poles of the motor. The stator teeth 32 are divided into quadrants, each containing an equal number of teeth, the quadrants being separated by the teeth 33. A set of four-pole windings 34, whose coils are connected in series as shown in Fig. 6, are provided, these windings passing around the teeth 32 of each quadrant and being separated by the teeth 33. A second set of bipolar windings 35 are provided, whose coils are likewise connected in series, these windings each passing around the teeth of two sets of successive quadrants and the included tooth 33 and being spaced apart by the alternate teeth 33. The four-pole windings are preferably formed of a greater number of windings of smaller wire than the bipolar windings. A third set of windings 36 is provided within the bipolar windings, these windings each passing around one of the teeth 33 and an equal number (in the form illustrated, one) of the teeth 32 on each side thereof. The windings 36, which are out of phase with the remaining windings, are likewise connected in series with each other.

By the use of the windings described, the speed of rotation of the bow-shafts and the consequent volume of tone may be readily controlled. The windings 36 may be employed together with the other windings 35 as starting windings for the motor. In

normal operation, a controlled speed of rotation of the bow shafts is secured by means of the four-pole windings 34, the polarity of which is then caused to be dominant. 5 A more rapid rate of rotation is secured by passing the current through the bipolar windings 35 alone. If a slower rate of rotation and a lower volume of tone are desired, the phase windings 36 are placed in 10 shunt with the other windings, through which current flows in series as in normal operation.

The operation of the device is more clearly illustrated by Fig. 6, which shows 15 diagrammatically the electrical interconnection of the various parts, which are here given the same numerals as in the preceding figures of the drawing.

Two main lead lines 40 and 41 are provided for the operating current, which in 20 the present instance, is an alternating current. The normal operating current, for rotation of the bow shafts at a normal rate to produce a normal volume of tone, the 25 current connection is from line 40 through the branch line 42 to the four-pole coils 34, through which the current passes in series. From the four-pole coils 34 the current passes through the connection 44 to the bipolar coils 35, through which it passes in 30 series. From the bipolar coils 35, the current passes directly into the lead line 41. As the bipolar coils 35 are constructed of fewer coils and of larger wire than the four-pole 35 coils 34, the flux produced by the latter is dominant and a normal rate of rotation is produced.

In order to produce a louder tone, suitable means are provided for increasing the 40 rate of rotation of the motor. For example, the current may pass from the line 40 into the contact roll 45. A perforated note sheet 46 passes over this contact roll. When a suitable perforation is provided in 45 the note sheet, contact is made between the roll 45 and the contact member 47, and current then passes through the line 48 which is directly connected to the connection 44 between the four-pole coils 34 and 50 the bipolar windings 35. Current then passes through the two bipolar windings 35 in series and thence to the line 41. The four-pole windings 34 are thus shunted out of the circuit and the polarity of the stator 55 of the motor is determined by the bipolar windings 35, with a consequent increase in speed of the rotor. In manual operation, the same effect may be produced by passing the current from the line 40 through the 60 line 40^a, the pedal contacts 45^a and 47^a and the connector 48^a, which is directly connected to the line 48 leading to the bipolar windings 35.

For slower rotation of the rotor of the 65 motor and a lower volume of tone, current

passes from the line 40 into the contact roll 45, through contact 49 when a suitable perforation is provided, thence through connector 50 to the split phase windings 36, through which it passes in series. From 70 the split phase windings 36 the current passes through a connector 51 to the line 41. Instead of employing the contact rollers 45 and the contact 49, this circuit may likewise be closed through the line 40^a, the pedal 45^b, 75 pedal contact 49^a and line 50^a. It will be noted that there is always a connection through the four-pole windings 34 and through the bipolar windings 35 in series at 80 all times, unless modified by the action of the control contacts. Consequently, when current passes through the contact roll 45 and the contacts 49 or through the corresponding pedal contacts just referred to, the circuit through the split phase windings 36 85 is in shunt with the circuit through the windings 34 and 35. Consequently, current at this time passes through all of the windings, that through the split phase windings being in shunt and the rate of rotation of the rotor 90 is materially decreased. The note playing circuits are controlled independently of the circuits through the windings of the motor controlling its speed. For example, when contact is made between the contact roll 45 95 and the note playing contact member 52, current passes through the connection 53 to the fingering magnet 14^a, thence through contact 54 to the bow shaft depressing electromagnet 25 and from this electromagnet 100 through the connection 55 to the line 41. This circuit operates without affecting the circuit through the bow motor.

The improved motor has been described as applied to the actuation of a bow shaft of 105 a stringed instrument and as controlled by a music-sheet, but no unnecessary limitation should be understood therefrom, but the appended claims should be construed as broadly as permissible in view of the prior 110 art.

I claim:

1. In an alternating current motor, a squirrel cage rotor, a stator having individual sets of four-pole windings connected 115 in series, bipolar windings connected in series and split phase windings connected in series, connections joining the four-pole windings and the bipolar windings in series, means for cutting out the four-pole windings to impart an increased rate of rotation to the rotor, and means for permitting passage of a shunt current through the split phase windings to decrease the speed of rotation of the 120 rotor.

2. In an alternating current motor, a squirrel cage rotor, a stator having individual sets of four-pole windings connected in series, bipolar windings connected in series and split phase windings connected 130

- in series, means for permitting passage of current either through the four-pole windings and the bipolar windings in series or through the bipolar windings alone, and
- 5 means for permitting passage of a shunt current through the split phase windings to decrease the speed of rotation of the rotor.
3. An alternating current motor having a squirrel cage rotor, a stator having independent sets of windings, one set forming a greater number of poles than the other, a third set of windings out of phase with the first-mentioned sets of windings, means permitting passage of current normally in
- 10 series through the first-mentioned sets of windings, independent means for cutting out one of said sets of windings, and means for permitting the passage of current through the third set of windings in shunt
- 15 with the first-mentioned sets of windings.
- 20 4. In an alternating current motor, a squirrel cage rotor, a stator having independent sets of windings, one of said sets of windings forming twice the number of poles formed by the other set and being wound to produce a stronger magnetic flux, and means permitting passage of current normally through both sets of windings in series.
5. In an alternating current motor, a squirrel cage rotor, a stator having independent sets of windings, one of said sets of windings forming twice the number of poles formed by the other set and being wound to produce a stronger magnetic flux, means
- 25 permitting passage of current normally through both sets of windings in series, and means for cutting out the set of windings forming the greater number of poles to vary the speed of the rotor.

HENRY K. SANDELL.
